Pierre Barnes
ATTORNEY

UNITED STATES PATENT OFFICE.

FRANK S. LANG, OF SEATTLE, WASHINGTON.

COOKING STOVE.

Application filed June 20, 1925. Serial No. 38,425.

This invention relates to cooking-stoves and is in the nature of an improvement in devices illustrated and described in U. S. Patent No. 990,884 issued to me May 2, 1911.

6 The object of the present invention, generally, is the perfecting of stoves of this character.

More specific objects and advantages of the invention will appear in the following specification.

10 The invention consists in the novel construction, adaptation and combination of parts, relating more especially to the fire box, the flue system and the means for regulating 15 the same, as hereinafter described and claimed.

In the accompanying drawing,—

Figure 1 is an end elevation of a stove embodying my invention; Fig. 2 is a longitudinal vertical section of the same; Fig. 3 is a view similar to Fig. 2 illustrating parts shown therein to an enlarged scale; Fig. 4 is a transverse section taken substantially on line 4—4 of Fig. 3; and Fig. 5 is a view of 25 the fire-box liner-plates which are shown assembled in Figs. 3 and 4, said liner-plates being disposed to afford a face view of each.

In said drawing, the reference numeral 10 represents one of the end walls of the stove shell, the other end wall is designated by 11; 30 12 is the front wall, and 13 is the back wall; said walls extending from the bottom wall 14 to the stove top 15. Within the stove shell is an oven which, as shown in Fig. 2, is formed to provide a relatively large portion 35 16 having a top wall 17, end walls 18 and 19, and a floor wall 20, which oven walls are disposed in spaced relations respectively with the top wall 15, end walls 10 and 11, and the bottom wall 14 of the stove shell or casing.

40 Extending from the oven portion 16 and of less depth than the latter is an extension 21 having a top wall 22; the end wall 10 of the stove shell serving as the end wall for said oven extension, and to which end wall 10 the floor 20 of the entire oven extends.

Such form of oven affords in a stove of 45 small size an extremely wide oven space between the walls 10 and 19 to accommodate pans of large size. The fire-pot of the stove is provided in the space above the top wall 22 of the oven extension 21 and between the walls 10 and 18. This fire-pot communicates through a horizontal flue 23 located above 50 the oven, and a downflow flue 24 provided be-

tween the walls 11 and 19, with a horizontal return flue 25 provided below the oven floor 20. The last named flue 25 has an outlet 26 (Fig. 2) opening into an exhaust flue 27, Fig. 4, from the top of which it connects with 60 the chimney pipe 28. An opening 29 in the wall 13 provides direct communication between the fire-pot and the upper portion of said exhaust flue. This opening 29 is, however, closable—fully or partly—by means of 65 a damper 30 (Fig. 4) which is regulated as by means of a controlling rod 31 connected to the damper arm 32, shown in Fig. 1. Provided within the fire-pot are liners, shown detached in Fig. 5, of brick or metal. 70

More particularly, said liners comprise an imperforate bottom or floor member 33, end members 34 and 35 and side members 36 and 37. The bottom member 33 consists of a plate having a plane central portion with depending spaced apart legs or ribs 38 to support the member above the fire-pot floor 22 with an air duct 39 therebetween. 75

Extending upwardly from the front and rear edges, respectively, of the plane central portion of the liner 33 are flanges 40 and 41 which are inclined, as shown in Fig. 3, to have their upper ends contact with the fire-pot walls 10 and 18.

The flange 41, however, is recessed as at 42 (Fig. 5) to provide a channel for the passage 80 of air between the wall 18 and the flange 41 into a duct 43 thereabove back of the liner 34. As shown in Fig. 3, the liner 34 is supported upon a shoulder 44 of the flange 41 back of 90 protuberances such as 45 of the referred to flange.

As shown, the front liner 35 is supported upon the bottom liner 33 and between protuberances 46 thereof and the flange 40. The 95 liner is held in such relation with respect to the casing wall 10 so as to afford a duct 47 for the passage of air between draft openings 48 provided in the upper portion of the casing wall 10 and ports 49 which are provided 100 in the bottom of the liner 35 immediately above the bottom liner 33 of the fire-pot. 50 represents a grid damper for regulating the effective sizes of the draft openings 48 to control the supply air which it is desired to admit below the fuel in the fire-pot for combustion purposes. 105

Also provided in the stove casing end wall 10 is a series of apertures 51 through which is supplied what may be termed secondary 110

combustion air into the duct 39 whence such air passes through the duct 43 to eventually escape through apertures 52 of the liner 34 into the fire-pot above the fuel. The apertures 52 are disposed to direct the secondary air passing therethrough downwardly and for which purpose such apertures are located in the underside of a nose element 53 formed on the liner.

10 The embodiment of the invention illustrates a wood burning furnace, although not confined to the use of such fuel as a grate of known construction may obviously be employed within the fire-pot above the elevation 15 of the ports 49.

In operation, the damper plate 30 is retained in its open position to afford a direct passage between the fire-pot and the chimney connection until the fire is burning suitably.

20 The damper plate is then moved into its closed position, whereupon the gaseous products of combustion are compelled to pass in a circuitous path through various flues before reaching the chimney connection.

25 By thus directing the hot combustion products, the heating of the oven is effected, and which, inversely, renders the oven walls 18 and 22 hot to coact with the hot liners 33 and 34 for preheating the secondary air prior to 30 its delivery through the aperture 52 into the fire-pot. It is to be noted that the primary air is admitted in a substantially horizontal direction into the bottom of the combustion space, and that the secondary air is admitted 35 into the upper rear portion thereof to ensure, as nearly as practical, the complete burning within the fire-box of the combustible portions of the fuel. Such arrangement of the two series of air inlets tends to effect within the 40 fire box a circulatory motion of gases which causes a more intimate mixture of the air with the combustible gases derived from the fuel.

While I have illustrated and described the embodiment of the invention now preferred 45 by me, I do not wish to be understood as con-

fining myself specifically thereto except as limited by the following claims.

What I claim is,—

1. In a cooking-stove, a fire-pot, liners therefor, said liners including a front member having ports below an imperforate lower portion, and an imperforate floor member extending between the front and back members, said liners being arranged to provide within the fire-pot two ducts for the admission of air into the combustion space inclosed by said liners, one of said ducts discharging air through the ports of said back member into the upper rear portion of said space and the other duct discharging air through the ports of said front member into the lower front portion of said space and immediately above said floor member, and means for controlling the last mentioned duct whereby air for combustion purposes is supplied exclusively into the upper rear portion of the combustion space.

2. A cooking-stove having an oven provided in one corner thereof with a reentrant angle, a fire-pot located in said angle, an exhaust flue extending rearwardly from the fire-pot, said fire-pot being provided with air inlet openings disposed at different elevations, a grid-damper for the upper of said inlet openings, and liners provided within the fire-pot to cooperate with a wall of the fire-pot to provide an air duct extending from the upper of said inlet openings to the lower front portion of the fire-pot, and a second duct extending from the lower of said inlet openings through the fire-pot into the upper rear portion of the space which is inclosed by the fire-pot liners, neither of said ducts communicating with said exhaust flue except through the medium of the space enclosed by said liners.

Signed at Seattle, Washington, this 20th day of May, 1925.

FRANK S. LANG.
